DESIGN FOR A PICTURE FRAME

Maxwell D. Moglen, New York, N. Y.

Application February 2, 1944, Serial No. 112,415

Term of patent 3½ years

(Cl. 29—20)

To all whom it may concern:

Be it known that I, Maxwell D. Moglen, a citizen of the United States of America, residing in New York, county of New York, and State of New York, have invented a new, original, and ornamental Design for a Picture Frame, of which the following is a specification, reference being had to the accompanying drawing, forming part thereof.

The figure on the drawing is a perspective view of a picture frame showing my new design.

I claim:

The ornamental design for a picture frame, substantially as shown.

MAXWELL D. MOGLEN.
